UNITED STATES PATENT OFFICE.

MARY BUSCH, OF McARTHUR, NORTH DAKOTA.

PIN-GUARD AND ORNAMENT.

1,115,280.

Specification of Letters Patent.

Patented Oct. 27, 1914.

Application filed May 2, 1913. Serial No. 765,114.

To all whom it may concern:

Be it known that I, MARY BUSCH, a citizen of the United States, residing at McArthur, in the county of Pembina and State 5 of North Dakota, have invented certain new and useful Improvements in Pin-Guards and Ornaments, of which the following is a specification.

My invention relates to improvements in 10 combined ornaments and pin guards, and one object of the invention is the provision of an article which will provide an ornament and at the same time produce a guard or protector for the point of the pin used in securing the hat.

Another object of my invention is the provision of a device which will provide an ornament for the hat and which will also protect the point of the pair of pins used in 15 securing the hat the device being highly ornamental and useful and being capable of production at the right price.

Another object of my invention is the provision of an article which may be used upon 20 the hat and for protecting the securing pins, and which may also be used as a combined brooch and necklace, as circumstances require.

With these objects in view my invention 25 consists of an article of the character and for the purpose stated embodying novel features of construction and arrangement of parts substantially as disclosed herein.

In order that the construction in detail 30 and the manner of using my article may be fully understood and its points of merit be appreciated I have illustrated in the accompanying drawings an article constructed in accordance with my invention.

Figure 1 represents a perspective view of 35 a hat with my device in position thereon, to illustrate its use in this connection and as a hat ornament and pin guard. Fig. 2 represents a plan view of the complete article or 40 device detached, and Fig. 3 represents a sectional view of one of the pin guard members and ornaments.

In the drawings: the letter A, designates the hat in connection with which my device may be used, said device consisting of the 50 ornament B, in the form of a brooch, provided with an attaching pin C, and with a pendant or ring D, from which leads the pair of chains E, which are also connected with the rings or eyes F, upon the hollow 55 buttons or ornamental members G, in which hollow members are placed the rubber fillings H, having the projections J, extending from said members and adapted to be engaged by the pointed ends K, of the pair of 60 hat securing pins L.

From this construction it will be seen that my device provides both an ornament as well as a guard or protector for the pin, or if desired the article may be used as a combined 65 brooch and necklace with the chains passing around the neck and secured by means of the hooks M, on the pair of ornament members, said members of course being made of any size or shape and ornamented in any desired 70 manner.

It will be apparent that I provide a device which while highly ornamental and attractive in appearance is also very useful and may be produced at the right price according to the design of the article and the 75 material used.

I claim:

A device of the character described, consisting of a brooch having securing means 80 adapted to be fastened to a hat, a pair of chains secured to said brooch, a part secured to the end of each chain and adapted to act as a pin-point protector, an interlocking connection secured to said parts, whereby said 85 parts may be connected and the device as a whole be used as an ornament.

In testimony whereof I affix my signature in presence of two witnesses.

MARY BUSCH.

Witnesses:

G. G. THOMPSON,
F. A. WARDWELL.
